UNITED STATES PATENT OFFICE.

JOHN S. KRAMER, OF STEGER, ILLINOIS.

LOCKING DEVICE FOR DRAWERS.

1,352,902.

Specification of Letters Patent. Patented Sept. 14, 1920.

Application filed June 23, 1919. Serial No. 306,224.

To all whom it may concern:

Be it known that I, JOHN S. KRAMER, a subject of Austria-Hungary, residing at Steger, in the county of Will and State of Illinois, have invented new and useful Improvements in Locking Devices for Drawers, of which the following is a specification.

This invention relates to bureaus, dressers and other similar articles of furniture, and its object is to provide a novel and improved arrangement of drawers and means for locking the same.

The objects stated are attained by means of a combination and arrangement of parts to be hereinafter described and claimed, and in order that the same may be better understood, reference is had to the accompanying drawings, forming a part of this specification.

20 In the drawings,

Figure 1 is a perspective view of the bureau;

Fig. 2 is a central cross-section thereof;

Fig. 3 is a cross-section taken adjacent to one end of the bureau, with certain drawers omitted;

Fig. 4 is a perspective view of a drawer lock;

Fig. 5 is a plan view of one of the drawers;

Fig. 6 is a perspective view, partly broken away, of a drawer or slide associated with the drawer shown in Fig. 5;

Fig. 7 is a perspective view, partly broken away, of the drawer shown in Fig. 5, with the slide of Fig. 6 omitted;

Fig. 8 is a detail in perspective of certain parts of the drawer lock;

Fig. 9 is a detail in perspective showing another drawer lock, and

40 Fig. 10 is a perspective view of a drawer controlling said lock.

Referring specifically to the drawings, the frame of the structure comprises a back 1, end walls 2, a top 3 and corner posts 4 which extend for a short distance below the bottom of the structure to serve as supporting legs. The design of the structure is such that it has the general appearance of a bureau or dresser.

50 On the top 3, at the ends thereof, are drawers 5 and 5^a which are housed in casings 6 and 6^a, and the top in the space between these casings serves as the instrument board of a talking machine shown diagrammatically in Fig. 2. A lid or cover closing down on the top 3 and over the tone arm 7 and turntable

8 of the talking machine is shown at 9. The horn 10 of the machine extends from the top 3 down into a compartment 11 closed in front by two doors 12 on the back of which may be 60 mirrors.

On opposite sides of the compartment 11, between the latter and the end walls 2, are drawers 13, and below the compartment and the drawers are located two wide drawers 14 65 and 15 extending throughout the entire width of the bureau between the end walls 2 thereof, and located one above the other.

The following locking means for the bottom drawers 14 and 15 are provided: 70

In a dovetailed longitudinal slot 16 in the bottom of the drawer 5 is slidably mounted a block 17 carrying a combination lock, the knob of which is shown at 18 and the bolt at 19. That portion of the block from which the bolt is to be projected is below the bottom of the drawer, and the bolt moves in a direction transverse of the drawer. The bolt is normally retracted flush with the side of the block, but when a predetermined combination has been worked out, a turn of the knob projects the bolt a certain distance; or, 80 a lesser distance if a different combination is used.

The purpose of the bolt 19 is to depress a 85 pair of cams 20 pivoted at 21 in a recess 22 in the top 3 beneath the bottom of the drawer 5. Each cam 20 is connected to a downwardly extending rod 23 connected to one end of a lever 24, to the other end of which 90 latter is connected a rod 25. The lever 24 is fulcrumed to one of the end walls 2, as shown at 26, and to a suitable support 27 on the back or rear wall 1 is fulcrumed a lever 28 to one end of which the rod 25 is connected. The 95 other end of the lever 28 is connected to a spring latch 29. One latch is provided for the drawer 14 and another latch for the drawer 15, with a cam 20 and the connections hereinbefore described for each latch so that 100 the drawers may be independently locked and unlocked.

The cams 20 are set staggered and located in the path of the bolt 19 when the latter is advanced. It will therefore be seen that 105 when the block 17 is slid forward the projecting bolt will depress one of the cams first, or it will clear this cam and depress the next one. Which cam is to be depressed will depend on the extent to which the bolt is projected, and as one of the cams controls the lock of one of the drawers, and the other 110

drawer lock is controlled by the other cam, the locks are independently controlled. When the cams are depressed the rods 23 swing the levers 24 and the latter, through the rods 25, operate the levers 28 to depress the latches 29 to which the latter are connected. The latches are normally positioned in front of the downwardly extended rear walls of the drawers, in which position of the latches, the drawers are held locked, but when the latches are forced down clear of said walls, the drawers are unlocked and may be now pulled open. The drawers are preferably automatically opened by spring drawn hooks 30 which engage the back of the drawers. Upon closing the drawers, the parts are reset with the assistance of springs 31 connected to the levers 24.

The end walls 2 of the bureau have roller bearing supporting moldings 31^a for facilitating movement of the drawers 14 and 15, and also ribs 32 which slidably fit in grooves 33 in the sides of said drawers to keep the latter from rising when slid in and out. The rods 23 are adjustably connected to the levers 24 by clamp sleeves 34 so as to make the action of the locking mechanism accurate.

Referring now to Figs. 5 to 8, the small top drawer 5 has its rear end open, and its side walls have slide ribs 36 to guide a slide or false drawer 37 having grooves 38 in which the ribs seat. When this double drawer is opened, all that is visible is the false drawer 37, which latter has two compartments 39 for small articles wanted handy. The compartments are of different depths to clear certain mechanism in the drawer 5.

In order that the false drawer 37 may always be in front and readily accessible, it is held in such position by a spring latch 40 accessible through an opening 40^a in an inclined wall 41 and acting on a keeper 42 on the inner face of the front of the drawer 5. When the false drawer is to be moved back, the latch is released, and then the drawer is automatically drawn back by a spring 43 acting on a slide bolt 44 which is held back by a stop plate 45. When the drawer 37 is pulled forward and closed, the spring 43 is placed under tension.

The drawer 37, when closed, conceals the knob 18 of the locking device hereinbefore described, and the knob is therefore not accessible until the drawer is slid back to uncover the same. The floor molding 47 shown in Fig. 8 is designed to keep the drawer 5 elevated to the proper height for the operation of the block 17.

Figs. 9 and 10 show a device that ordinarily prevents the drawers 14 and 15 from being pulled entirely out of the bureau, and yet permitting this when the top drawer 5^a is drawn out. The floor of the casing 6^a inclosing the drawer 5^a supports a down-

wardly extending vertical rock shaft 50 having at its upper end a laterally projecting cam arm 51. A spring 52 connected to the shaft 50 tends to turn it in a direction to hold the cam arm 51 as shown in Fig. 9. The drawer 14 (as well as the drawer 15) has a side groove 53 into which a side pin 54 carried by the rock shaft 50 projects when the latter is given a partial turn.

With the parts as shown in Fig. 9, the drawer 5^a being removed, the drawer 14 may be inserted or removed, but when the drawer 5^a is inserted into its casing 6^a, a cam 55 on the bottom of said drawer (see Fig. 10) engages the cam arm 51 and rocks the shaft 50 so that the pin 54 enters the groove 53, thereby preventing removal of the drawer 14. It will be understood that the shaft 50 has another pin lower down for locking the drawer 15.

The block 17 is provided with a handle 46 for the manipulation thereof.

Below the compartment 11 the bureau may be fitted with a concealed shelf 56, which when drawn out affords a handy place for toilet articles or preparations.

I claim:

1. The combination of a pair of slidable drawers, independent locking means for the drawers, operating means for the locking means, a third drawer, and an actuator in said third drawer adjustable to selectively engage the aforesaid operating means.

2. The combination of a pair of slidable drawers, independent locking means for the drawers, operating means for the locking means, a third drawer, and an actuator carried by the third drawer and slidably positioned therein for engagement with the aforesaid operating means, said actuator being adjustable to selectively engage said operating means.

3. The combination of a pair of slidable drawers, a lock for one of the drawers, operating means for the lock, actuating means for the operating means carried by the other drawer, and a slide in the last-mentioned drawer concealing the actuating means.

4. The combination of a pair of slidable drawers, a lock for one of the drawers, operating means for the lock, a slide block carried by the other drawer, and a lock-controlled bolt carried by the slide block, said bolt when projected being intercepted by the operating means.

5. The combination of a pair of slidable drawers, a lock for one of the drawers, a slide block carried by the other drawer, a lock-controlled bolt carried by the slide block, and operating means for the aforesaid drawer lock, said means including a cam member which is in the path of the aforesaid bolt when the latter is projected.

6. The combination of a pair of slidable drawers, a lock for one of the drawers, a

slide block carried by the other drawer, a lock-controlled bolt carried by the slide block, a lever for operating the aforesaid drawer lock, and a rod for operating the 5 lever, said rod having actuating means extending into the path of the aforesaid bolt when it is projected.

7. The combination of a pair of drawers, a rock shaft having a lateral pin, one of 10 the drawers having a longitudinal groove into which the pin is adapted to project, for preventing the withdrawal of said drawer, an actuating arm on the rock shaft, and

means on the other drawer engageable with said arm for operating the shaft. 15

8. The combination of a pair of drawers, a rock shaft having a lateral pin, one of the drawers having a longitudinal groove into which the pin is adapted to project, for preventing the withdrawal of said drawer, an 20 actuating arm on the rock shaft, and a cam on the other drawer engageable with said arm for operating the shaft.

In testimony whereof I affix my signature.

JOHN S. KRAMER.
